3,100,415 PIANO CASE

Clifford W. Andersen, De Kalb, Ill., assignor to The Wurlitzer Company, Chicago, Ill., a corporation of Ohio
Original application Oct. 14, 1955, Ser. No. 540,530.
Divided and this application Sept. 27, 1960, Ser. No. 58,662

6 Claims. (Cl. 84—177)

This invention is concerned with the musical arts, particularly with an electronic piano, and most specifically with a case therefore.

This application is a division of my copending application, Serial No. 540,530, filed October 14, 1955, and now abandoned.

The pianoforte, or piano, as it is generally termed, is an extremely popular musical instrument and is found substantially throughout the civilized world. The piano in its conventional form is quite large and heavy. Consequently, it is difficult to move a conventional piano, and a piano generally is limited to use in first floor locations, generally in the largest room in the house. This can be extremely undesirable from the standpoint of the student or casual pianist, and also from the standpoint of other persons occupying the same residence.

As a result, it has been proposed that the size and weight of a piano be reduced by the provision of an electronic piano. It is known that a tuned reed having an electrical potential applied to it and vibrated near a conductive member will form with that member a variable capacitor giving rise to an electrical oscillation which can be translated into a musical tone. I have found that when such a reed is percussively actuated, remarkably realistic piano tones can be produced if the various elements of the electronic piano are properly correlated, and the electrical oscillations generated are properly amplified and converted into audio oscillations. This invention is concerned with an electronic piano of this type.

It is an object of this invention to provide a case for an electronic piano wherein the sides and back of the case comprise a single section of molded plywood, this section being mounted on a bottom or base, and a top or cover being detachably mounted thereon.

Another object of this invention is to provide an improved detachable leg construction wherein the legs can be stored in the case for ready transportation of the entire piano.

More specifically, it is an object of this invention to provide an electronic piano of a portable nature wherein the piano legs are detachable from the case and are carried beneath the fall cover.

Other and further objects and advantages of the present invention will be apparent from the following description when taken in connection with the accompanying drawings wherein:

FIG. 1 is an exploded perspective view of the parts of a piano case constructed in accordance with the invention;

FIG. 2 is a perspective view of the parts of the case in assembled relation;

FIG. 3 is an enlarged vertical sectional view through the front portion of the piano, particularly the fall cover and assembly as taken substantially along the line 3—3 of FIG. 2;

FIG. 4 is a view generally similar to FIG. 3 but taken substantially along the line 4—4 of FIG. 2;

FIG. 5 is an oblique upward view beneath the fall cover as taken substantially along the line 5—5 of FIG. 3;

FIG. 6 is a fragmentary sectional view taken substantially along the line 6—6 of FIG. 4;

2

FIG. 7 is an enlarged fragmentary vertical sectional view taken substantially along the line 7—7 of FIG. 4;

FIG. 8 is an upwardly looking horizontal sectional view taken substantially along the line 8—8 of FIG. 7.

Reference now should be had to FIGS. 1 and 2 for a description of a piano case indicated generally by the numeral 32. It will be seen that the ends 138 and the back 140 of the case are made of a single sheet of plywood molded generally in accordance with conventional practices. The plywood sheet comprising the ends and back rests on top of a bottom 142, also formed of plywood, and of the same outline as the back and ends. The back and ends are glued to the bottom 142, and preferably also are secured with small nails or screws. The forward corners of the ends 138 are cut down or relieved as is indicated at 144 to provide end clearance for the keyboard. It will be appreciated that if the corners were not so cut down, the pianist might feel confined or "boxed in."

Blocks 62 are secured to the opposite end pieces 138 to rest on the bottom 142. The blocks 68 are glued to the ends and to the bottom, and also are secured to the ends by means of wood screws 146. Besides providing a mount for a reed bar assembly, not shown, these blocks also help to reinforce the joint of the case as will be appreciated. Blocks 91 are similarly secured to the ends of the case by gluing, and also by means of wood screws 148. The upper corners of the blocks 91 are relieved on the front edges thereof as will be seen at 150 to accommodate a main rail, not shown. In addition to the foregoing blocks, there also are blocks 152 secured to the ends near the fronts thereof which serve as filler blocks at the opposite ends of the keyboard, and which also support the fallboard assembly at the corners thereof as hereinafter will be apparent. In addition to the aforementioned blocks, there is a pair of cleats 154 secured to the ends 138 parallel to the top edges thereof and spaced slightly down from the top edges. A long cleat 156 lying in the same plane as the cleats 154 extends along the inner surface of the back 140 spaced down somewhat from the top thereof. These cleats are glued to the inside of the case, and also preferably are secured with nails or screws. The cleats 154 and 156 serve to support the top 158 which nests within the ends 138 and back 140.

The blocks 68 are predrilled at their tops as is indicated at 160 for receipt of the wood screws mounting the reed bar assembly. In addition, the top portions of the blocks 91 are horizontally drilled as at 162 before assembly with the case for receipt of bolts that secure the main rail to the blocks 91. Preferably the cleats 154 and 156 are drilled as at 166 for receipt of wood screws passed through apertures 168 in the top 158. These wood screws preferably have bevelled heads, and the apertures 168 are bevelled or countersunk for receipt of these heads.

The back 140 of the case is provided with a plurality of horizontal slots forming a louver 170 behind which a loud-speaker 48 is mounted, the louver passing sound from the front of the loud-speaker as will be understood. A somewhat similar louver 172 is provided in the top 158 substantially directly above the loud-speaker. This louver helps to control back loading of the loud-speaker, and also provides a path for sound from the backside of the speaker cone which is of different length than the path from the front. It has been found that the louver 172 in the top eliminates subtones. An additional pair of louvers 174 and 176 is found in the back and top respectively adjacent the opposite end from the first mentioned louvers. These louvers provide ventilation for

the amplifier which is mounted adjacent them, and also provide a balanced appearance for the piano. In addition to the foregoing apertures in the piano case, there is provided a rectangular opening 176 in the left end for alignment with the panel 50 bearing the various controls and pilot light, and there is a circular opening 178 adjacent the center of the back 140 for receipt of a detachable connector for a line cord to connect the piano to an electrical outlet.

The underside of the top 158 is provided near the front thereof with a cleat 180 having a bevelled front surface. The upper rear corners of the filler blocks 152 are provided with notches or cutouts 182 having bevelled or inclined rear or inner edges. The fallboard 184 of the fallboard assembly rests with its two lower corners in the cutouts or notches 182 while the upper edge thereof fits beneath the top 158 and rests against the front of the cleat 180. A plurality of wood screws fits through some of the apertures 168 along the front edge of the top and is threaded into suitable openings in the top of the fallboard 184. Preferably, the fallboard is predrilled for receipt of these screws. The fallboard carries a tray 186 on which music rests. In addition to the foregoing parts, the piano case includes a removable fallboard cover 188 which will be described in detail shortly hereinafter. The fallboard cover 188 overlies the keyboard and fallboard assembly when it is desired to transport the piano and it is held in place by suitcase type fasteners 190 having cooperating halves on the cover and on the top 158, and also on the cover and on the ends 138.

When the parts are generally in the condition shown in FIG. 1, that is the ends and back are assembled with the bottom, and also with a front piece or riser 190, the various blocks and cleats being affixed in place, but the the loud-speaker 48 not yet being mounted, the cleat 180 being mounted on the top 158, the tray 186 being mounted on the fallboard 184, and the various parts of the fall cover 188 being assembled as hereinafter will be described, the parts are sprayed with a lacquer. The lacquer covers the outside of the case, and also preferably covers the inside and provides a tough finish which is substantially marproof and which also is substantially waterproof. Legs 42 also are sprayed with the same lacquer to provide the legs with a pleasing appearance, and with a finish which is substantially marproof and waterproof.

Referring now in greater particularity to the fall cover 188, and in this regard reference should be had also to FIGS. 3-6, it will be seen that the fall cover 188 comprises a top 192, a front 194 butted against the top, and a pair of end pieces 196 butted against the top and front. These parts of the fall cover are glued together, and also preferably are secured with nails or screws. It will be appreciated that the top, front, and end of the fall cover are complementary to the corresponding parts of the case as heretofore described to provide a rectangular front section for the case. A cleat or reinforcing bar or rib 198 lies along the junction of the top and front along the inner portion thereof to reinforce the joint, the top and front being glued, and preferably also screwed or nailed to this cleat.

At the opposite ends of the fall cover there is provided a pair of diagonally disposed wooden mounting blocks 200 which are glued to the ends, and which also are secured by screws 202. In addition, the wooden mounting blocks 200 are provided with inserted metal sleeves 203 having internal threads. These sleeves are designed to receive the threaded studs 204 (see also FIGS. 7 and 8) extending from the ends of the legs 42. These studs 204 are threaded a substantial distance into the legs at the upper ends thereof, and the upper ends of the legs are provided with metal ferrules 206 to provide an ornamental appearance and positively to prevent splitting of the upper ends of the legs. The lower ends of the legs also are provided with metal tips of ferrules 208 to protect the same.

Adjacent the center of the fall cover 188 there is provided a brace or rest 210 having a scalloped lower surface providing four semicircular recesses. The entire lower surface including the semicircular recesses is lined with felt as indicated at 212 and the semicircular recesses are designed to receive the legs 42 when they have the studs 204 at the upper ends thereof threaded into the metal sleeves 203. A flexible strap 213 is secured at one end as at 214 permanently to the brace or support 210, and at the other end is connected by means such as a snap fastener 216 to this brace or support whereby the legs can be held tightly up against the felt lined semicircular recesses.

In accordance with the foregoing, the entire piano can be carried as a unit somewhat resembling an oversized suitcase, the legs being stored beneath the fall cover as readily may be seen in the dash lines in FIG. 2. A handle 218 is provided on the front of a fall cover for carrying the piano, and this handle preferably is flexibly connected to the fall cover for ease in carrying. The back of the piano case is provided with a plurality of wooden cleats, not shown, serving as feet on which the case may be rested when it is carried by means of the handle 218. It will be understood that these cleats preferably are applied before the lacquer is sprayed on the case.

The means by which the legs 42 are mounted on the piano case is shown in FIGS. 3, 4, 7 and 8. A metal plate 222, conveniently of triangular outline, is mounted on the underside of the case near each corner thereof by means of machine screws 224 threaded into T-nuts 226 in the case. Each plate 222 is provided with a central angularly disposed section 228, preferably of circular outline, and each section 228 is provided with a central bore 230 which is threaded for receipt of the stud 204 of the corresponding leg 42. The angular disposition of the plate sections 228 angles the piano legs 42 outwardly as best may be seen in FIG. 4 for improved stability and more pleasing appearance. It will be understood that the threaded connection just described provides a convenient and readily operable detachable connection of the legs to the piano case.

The specific examples herein shown and described are to be understood as being for illustrative purposes only. Various changes in structure will no doubt occur to those skilled in the art, and such changes are to be understood as coming within the scope of the invention insofar as they fall within the purview of the appended claims.

The invention is claimed as follows:

1. In a portable piano, the combination comprising: a piano case of suitcase-like configuration having a keyboard and having a fall cover movable relative to the remainder of said case, said case including said fall cover being relatively wide and deep side-to-side and front-to-back and relatively low from top to bottom when in horizontal playing position, said case comprising similar substantially rectangular top and bottom walls having a major dimension along the width of said case and a minor dimension from front-to-back of said case, said case further having a peripheral wall having a predetermined height less than either dimension of the top and bottom walls; said fall cover covering said keyboard with the upper portion of said fall cover substantially coplanar with the top surface of the remainder of the case and with the under surface of said upper portions spaced above said keyboard, said fall cover including a top panel forming a part of said top wall, a front panel forming a part of said peripheral wall, and a pair of opposite end panels interconnecting said top and front panels and forming parts of said peripheral wall; fastener means detachably securing said fall cover to the remainder of said case; a plurality of legs the axial dimension of which is less than the major dimension of said fall cover; threaded fastening means at one end of each of said legs; complementary threaded fastening means on said case bottom wall for

detachably mounting said legs in depending relationship to said case for supporting said case; threaded fastening means at opposite ends of said fall cover on the inside of said end panels for securing some of said legs at one end of said fall cover and the remainder of said legs at the other end of said fall cover in partially overlapping relationship with the first mentioned legs; means intermediate the ends of said fall cover for securing the overlapping portions of said legs; and a handle secured to said peripheral wall and of a size to be grasped by the hand for carrying of said case in depending position from said handle.

2. The combination according to claim 1 wherein the intermediate securing means comprise a member having a plurality of recesses therein, each of said recesses receiving one of said legs, and a flexible member overlying said recesses and holding said legs in said recesses.

3. The combination set forth in claim 2 wherein the intermediate securing means member is triangular in shape having two sides and a hypotenuse, the sides respectively lying against the top panel and front panel of the fall cover and the plurality of recesses being in the hypotenuse.

4. The combination as set forth in claim 1 wherein the handle is mounted on the front panel of the fall cover.

5. The combination set forth in claim 1 wherein the end panels of the fall cover each have a curved edge remote from the top and front panels, the adjacent portions of the remainder of the peripheral wall being complementary thereto.

6. A portable piano comprising: a relatively wide case of suitcase-like configuration; said case being relatively wide and deep side-to-side and front-to-back and relatively low from top to bottom when in horizontal playing position, said case comprising similar substantially rectangular top and bottom walls having a major dimension along the width of said case and a minor dimension from front-to-back of said case, said case further having a peripheral wall having a predetermined height less than either dimension of the top and bottom walls; a plurality of legs detachably secured at their upper ends to the bottom wall of said case to depend therefrom for supporting said case; a keyboard at the front end of said

5

10

15

20
